CLAIM

The ornamental design for a camera, as shown and described.

DESCRIPTION

FIG. 1 is a perspective view of a first embodiment of a camera showing our new design;
FIG. 2 is a front view thereof;
FIG. 3 is a rear view thereof;
FIG. 4 is a left side view thereof;
FIG. 5 is a right side view thereof;
FIG. 6 is a top view thereof;
FIG. 7 is a bottom view thereof;
FIG. 8 is a perspective view of a second embodiment of the camera;
FIG. 9 is a front view thereof;
FIG. 10 is a rear view thereof;
FIG. 11 is a left side view thereof;
FIG. 12 is a right side view thereof;
FIG. 13 is a top view thereof; and,
FIG. 14 is a bottom view thereof.

The broken lines illustrate portions of the camera and form no part of the claimed design.

1 Claim, 8 Drawing Sheets
